UNITED STATES PATENT OFFICE.

WALLACE H. FOSS, OF CAMBRIDGE, MASSACHUSETTS, ASSIGNOR TO W. H. FOSS CO., INC., OF BOSTON, MASSACHUSETTS, A CORPORATION OF MASSACHUSETTS.

SHANK-STIFFENER.

1,261,917.

Specification of Letters Patent. Patented Apr. 9, 1918.

Application filed October 19, 1917. Serial No. 197,500.

To all whom it may concern:

Be it known that I, WALLACE H. Foss, a citizen of the United States, and resident of Cambridge, county of Middlesex, State of Massachusetts, have invented an Improvement in Shank-Stiffeners, of which the following description, in connection with the accompanying drawing, is a specification, like characters on the drawing representing

10 like parts.

In the patent to Joseph E. Peckham No. 1,240,249, granted September 18, 1917 there is illustrated and described a shank stiffener for boots and shoes which comprises a flexible body portion curved longitudinally to conform to the shank and provided on its convex face with a longitudinally-extending groove situated centrally of the body, the formation of the groove causing the total thickness of the body portion to be greater than that of the material from which it is made, a stiff resilient metal wire embedded in said groove and curved longitudinally to conform to the curvature of the body portion, said wire being retained in the groove by means such as staples which permit a relative longitudinal movement of the wire and body portion when the shank stiffener is flexed during use.

30 In the shank stiffener illustrated in the said patent the wire is shown as of uniform diameter throughout its length, and while a wire thus constructed functions properly to provide the necessary stiffness and resiliency to the device, yet I have found from experience that some times the wire will become displaced longitudinally. I have also found that if a narrow shank, such as would be used in ladies' shoes, is twisted longitudinally, the wire will sometimes turn on its axis so that the curvature of the wire will be reversed from what it should be.

The object of my invention is to improve the shank stiffener illustrated in the said 45 patent so as to eliminate the above-mentioned disadvantages without, however, sacrificing any of the advantageous features of the device.

A shank stiffener embodying the present 50 invention is similar to that described in said patent in that it has the flexible body portion curved longitudinally to conform to the shank and depressed longitudinally along the medial line of the convex side to form a 55 groove and cause the total thickness of the

body portion to be greater than the thickness of the material from which it is formed, and also in that it has a stiff resilient metal wire embedded in the groove and curved longitudinally to conform to 60 the curvature of the body portion. In the present invention, however, the wire is made with spatuliform ends which rest flatly against the body portion and the staples by which the wire is secured to the body 65 portion are positioned so that they embrace the wire at each end at the point where the round wire merges into the flattened or spatuliform portion thereof. The positioning of the staples in this location prevents 70 any undesirable longitudinal movement of the wire on the shank in either direction, while at the same time permitting all necessary relative longitudinal movement of the wire and body portion when the shank stiffener 75 flexes or bends in ordinary use. The spatuliform ends of the wire also function to prevent the wire from turning on its axis. With my improvement, therefore, the wire is invariably held in its correct position at 80 all times.

In order to give an understanding of my invention, I have illustrated in the drawings a selected embodiment thereof which will now be described, after which the novel features thereof will be pointed out in the appended claims.

Figure 1 is a perspective view of a shank stiffener embodying my invention;

Fig. 2 is a section on the line 2—2, Fig. 1;

Fig. 3 is a longitudinal section on the line 3—3, Fig. 1;

Fig. 4 is a view of the metal wire element of the stiffener.

In the drawings, 1 indicates the body 95 portion of the shank stiffener which may be made of leather-board or any other suitable material. This body portion is curved longitudinally to conform to the shank and is also provided with a longitudinal groove 100 2 on its convex face, the groove being herein shown as situated centrally of the body portion. The formation of this groove results in giving to the body portion a total thickness which is greater than the thickness of 105 the material from which it is formed, as described in the aforesaid patent. The resilient reinforcing wire is indicated at 3, and this is made from relatively-stiff metal wire which is circular in cross-section. The 110

wire 3 is beat longitudinally to conform to the curvature of the body portion 1 and is embedded in the groove 2. The wire may be held in the groove in any suitable way. 5 I have herein shown for this purpose two staples 4 which embrace the wire and are inserted through the body portion and then are clenched on the concave face of the body portion.

10 In my improved structure the ends of the wire 3 are flattened, as shown at 5, these flattened ends being so shaped that when the wire lies in the groove 2, the flattened ends 5 lie flatly against the face of the body portion, as seen clearly in Fig. 1. In thus producing the flattened or spatuliform portions 5 of the wire, I preferably do this in such a way that the ends are widest at the extremity and have a progressively-decreasing width 15 toward the body of the wire. Further, these flattened portions are thinnest at the extremity and have a gradually-increasing thickness toward the round portion of the wire. 20

25 The securing staples 4 are positioned so that they embrace the wire 3 at the point where the round portion and the spatuliform portion of the wire merge together, and said staples are so shaped that the sides or legs 30 thereof closely embrace the wire, as seen clearly in Fig. 2. The advantage of this construction is that thereby the wire is held invariably in proper position longitudinally, while at the same time any relative movement 35 of the wire and body portion which results from the flexure of the shank stiffener is freely permitted. For instance, in Fig. 1, the right-hand staple 4 coöperates with the flattened right-hand end of the wire to prevent longitudinal movement of the wire to the left and similarly coöperation of the 40 left-hand staple 4 and left-hand flattened

end 5 of the wire prevent longitudinal movement of the wire to the right. Moreover, the flattened ends 5 of the wire coöperate 45 with the staples 4 to prevent the wire from turning about its axis because the staples 4 hold the wire firmly against the body portion and the engagement of the flattened ends 5 with the faces of the body portion 50 prevent the turning movement of the wire.

I claim:

1. A shank stiffener comprising a body portion longitudinally grooved, a stiff, resilient metal wire situated in said groove, 55 the ends of the wire being flattened and resting against the face of the body portion, and two staples closely embracing the wire and securing the latter to the body portion, said staples being situated at the points 60 where the flattened ends merge into the unflattened portion of the wire.

2. A shank stiffener comprising a flexible body portion curved longitudinally and provided on its convex face with a longitudinally-extending groove, a stiff, resilient wire situated within said groove, the ends 65 of the wire being flattened and lying flatly against the face of the body portion, and means for retaining the wire in the groove, 70 which means coöperates with the flattened end portions of the wire to prevent longitudinal movement thereof.

3. A shank stiffener comprising a flexible body portion curved longitudinally and 75 provided on its convex face with a longitudinally-extending groove, a stiff, resilient wire situated within said groove, the ends of the wire being spatuliform, and means securing said wire in said groove. 80

In testimony whereof, I have signed my name to this specification.

WALLACE H. FOSS.
